HONING OR POLISHING TOOL

Arnold Krastin, Cleveland, Ohio

Application February 3, 1941, Serial No. 377,173

6 Claims. (CL. 51—184.2)

This invention relates to a tool for performing surface finishing operations on hollow members, for example for honing hydraulic brake cylinders and the like.

An object is to provide a surface finishing tool which is self-fitting with respect to circular surfaces of different diameters.

Another object is to provide a surface finishing tool capable of applying, in a flexible manner and progressively around an internal circular surface, finishing operations of equal effective force at equally spaced regions.

A specific object is to provide a simple and inexpensive finishing tool for internal cylindrical surfaces, which tool can be mounted in the chuck of a portable machine on the order of an electric drill and driven thereby properly to perform honing or polishing operations on bores of different sizes without requiring precise alignment between the tool chuck and the work.

A still more specific object is to provide a tool for reconditioning hydraulic brake cylinders e. g. of automobiles when such cylinders become pitted or scored, which tool will operate properly both on the wheel cylinders and the master cylinders notwithstanding a considerable difference in diameters therebetween.

Other objects and the various novel features of the invention will become apparent from the following description of the illustrative embodiments shown in the drawing in which:

Fig. 1 is a side elevation of a brake cylinder honing or polishing tool incorporating the invention, portions of the assembly being shown in central longitudinal section;

Fig. 2 is an end view of the tool showing the relative position of parts prior to application to the work;

Fig. 3 is a sectional detail view of a preferred connection between the tool head and driving shaft or shank;

Fig. 4 is a major face view of a flexible abrasive strip adapted to be mounted on the tool head;

Fig. 5 is a view similar to Fig. 2 showing the relationship of parts when the tool is applied to the work, and

Fig. 6 is an end view of a modified form of tool, showing flexible tool blades thereof in normal position and showing, in broken lines, working positions of such blades.

Brake cylinders become pitted mainly by corrosion, and sometimes scored due to accumulation on the plunger or piston of abrasive foreign matter. Reborning of the cylinders in order to recondition them when pitted or scored requires

relatively great expense and always requires removal of the cylinders from the machine on which mounted. The present tool is capable of being used to recondition such cylinders at a considerable saving in time and expense generally; and its use does not, in many cases, require dismounting of the cylinders.

Referring to Fig. 1 the head 1 of the tool comprises, as shown, two strips of metal 2 and 3, secured together as by screws 4 and 5 which may enter the strips from opposite directions as illustrated so as to clamp between them flexible tool elements 15, 16 and 17 to be later more fully described. Each of the strips is threaded to receive one of the screws so that the strips may be drawn into clamping relation to the flexible elements. A driving shaft or shank 6 may comprise simply a section of round metal stock with one end secured between outstruck portions 7 of the head strips 2 and 3, as by a cross pin 8. The outstruck portions 7 of the head strips, as shown in Fig. 3, are oppositely curved in cross section and more or less loosely receive the end of the shaft between them when the strips 2 and 3 are in clamping position with respect to the flexible elements, and the pin is slightly loose in the receiving opening 9 of the shaft,—so that the head, in effect, has a universal joint coupling with the shaft. The universal coupling enables the head continuously to operate on a working axis somewhat at an angle to the axis of the driving chuck in which the shaft is gripped and rotated. Thus if the driving machine is portable an operator can hold the chuck sufficiently accurately in position by hand for proper operation; or if the machine is fixedly mounted the operator can hold the work by hand. The flexible elements 15, 16 and 17 also cooperate in enabling proper work to be done notwithstanding slight angular displacement of work and driving chuck axes.

The flexible element 15 is preferably a rectangular strip or leaf of light gage spring metal (e. g. phosphor bronze) so that unsupported end portions thereof can be easily flexed. The central part or portion 18 of the strip is preferably flat and extends a considerable distance beyond the head strips 2 and 3 at opposite sides thereof as gripped by the head strip, but the overall lateral extent of the portion 18 is less than the smallest diameter of cylinders to be surfaced. The central flat part of the spring element 15 has openings to receive the screws 4 and 5 of such size that said central part cannot be clamped in a position eccentric to the head. The free portions 20 of the spring element 15 beyond the attaching

or mounting flat portion 18 as shown in Fig. 2 are bent in opposite directions from the plane of the mounting portion, in expanding curved form i. e. spiral or other suitable curve, so that substantial end marginal portions of the spring element lie outwardly from the axis of the head greater distances than radii of the cylinders to be surfaced. The general S-shape of the spring element 15 in unstressed condition is preferred because this makes it easy to insert the tool into the cylinder to be surfaced. The spring element 15 could be made in two pieces with portions overlapped at the center of the head for attachment thereto.

The outwardly disposed faces of the expandingly curved portions 20 of the spring element 15 support or bear suitable abrasive for contact with the walls of the cylinder to be surfaced.

Preferably the abrasive is supported separately from the spring element 15, the elements 16 and 17 above referred to being in the form of flexible rectangular sheets or strips having abrasive grains on one side (e. g. emery cloth). Such strips, (one shown in Fig. 4) have slots 21 leading inwardly from one edge so that the slotted margins can be readily inserted between the spring strip portion 18 and the respective head strips 2 and 3 with the shanks of the clamping screws 4 and 5 occupying the slots. The screws need merely to be loosened in order to remove and replace the abrasive strips 16 and 17 as will be apparent.

With the arrangement of parts above described the flexible curved portions of the S-shaped spring element 15 and strips 16 and 17 can be fitted into substantially complementary relationship to cylinders of different diameters and the free portions of the spring arms apply approximately equal polishing or honing pressure and driving torque at opposite portions of the work surface to be honed or polished. Fig. 5 shows the working relationship of the curved spring portions and abrasive strips to a cylinder C to be honed or polished. All portions of the abrasive strips which contact with the cylinder C and all portions of the spring 15 which support said portions of the abrasive are in trailing relation to the connections thereof to the head 1; and the connections, by which driving torque is effected are flexible so that driving torque and abrasive pressure are flexibly applied. Due to the flexibility of the tool elements 15, 16 and 17 and the manner of supporting them it is apparent that, when the head 1 is rotated clockwise as shown in Fig. 5, practically the entire areas of each of the curved portions of the strips 16 and 17 can become effective in abrading the inner surface of the cylinder,—centrifugal force aiding the tendency of the free spring end portions to assume a form complementary to the cylinder and in accomplishing uniform working pressure at circumferentially spaced regions corresponding to the number of free spring portions used. This number may, of course, be increased. The abrasive pressure may be greater at portions of the spring element 15 near the attached portions 18 thereof or near the end portions or at intermediate regions, but always the zones of concentrated pressure are balanced circumferentially about the working axis of the tool head; and, due to the uniform flexibility of the spring element 15 at all free portions thereof lengthwise of the head the zones or regions of concentrated pressure will extend longitudinally of the work for the entire length 75

of the portion operated upon by the tool at a given time.

In order to assist in initially aligning the tool with the cylinder or other surface to be honed or polished I may provide tool-aligning members such as shown at 25. These, as shown, are pins which are threaded (e. g.) into necked portions 26 of the head strips 2 and 3, so that the pins can, in operative effect, be lengthened or shortened in accordance with the inner diameters of different elements constituting the work. The tool aligning members exert no pressure on the flexible elements, but simply serve, at the start of the honing or polishing operation, to secure approximate alignment of the tool driving chuck with the surface of the member to be honed or polished.

In order to simplify the matter of loosening and tightening the clamping screws 4 and 5, holes are provided in the spring element 15, as at 23 for reception of a screw driver,—the holes lying substantially opposite the heads of respective screws.

Fig. 6 illustrates three flexible members 15a which extend normally outwardly parallel to supporting surfaces of a triangular head 1a. Abrasive strips could be supported thereby in approximately the same manner as already described. In such case the triangular piece 1a would ordinarily be bar stock with a socket at one end to receive the driving shaft 6 and connecting pin 8, and the clamping strips 30 would be fastened to the triangular body as by three sets of screws 31. Alignment securing members 32, corresponding in operative effect to the members 25, are plates adjustable in and out on the outer faces of the clamping strips 30 (e. g. having slots to receive the shanks of the screws 31 to permit movement in and out on part of the alignment securing plates).

The arrangement according to Fig. 6 is characterized principally in that the spring leaves 15a are capable of operating to force abrasive against (e. g.) cylinders of greater variation in diameter than is possible by the arrangement according to Fig. 2 in the exact form illustrated, i. e. wherein the minimum diameter of the work is the length of the central portion 18 of the spring element 15. The arrangement according to Fig. 2 could be modified in accordance with Fig. 6, in other words could have wholly straight oppositely extending readily flexible spring arm elements.

I claim:

55. 1. A honing or polishing tool for internal circular surfaces, comprising a rotatable head and a plurality of flexible abrasive members extending outwardly therefrom with free portions adapted to extend in trailing relationship to the head in the working position of the members so that portions of the members are complementary to the circular surface, relatively separable substantially rigid clamping strips on the head, and releasable means supported by said clamping strips and operable to force the strips toward each other in a manner to cause the clamping strips to grip and hold portions of the flexible members between them.

70 2. A honing or polishing tool comprising a drive shaft adapted for rotation, a generally S-shaped one piece metallic leaf spring element, means lying on opposite sides of said element connected with the drive shaft and extending along the axis thereof beyond one end of the shaft for supporting said element intermediately

of its ends, and abrasive means supported by outwardly disposed portions of the arms of the S-shaped element for contact with the work.

3. In a honing or polishing tool, a head comprising a pair of superposed strips of relatively rigid material and means connecting the strips and operable to force the strips together, a shaft, means constituting a universal coupling between the strips and shaft, and flexible means clamped between the strips and adapted for pressing abrasive material outwardly against a circular surface when the shaft is rotated.

4. A honing or polishing tool comprising a rotatable head, flexible elements attached to the head and emanating therefrom and arranged to operate in contact with a circular surface in trailing relation to the attached portions of said elements, and means projecting laterally from the head in a manner approximately to center the head with reference to the work.

5. The arrangement according to claim 4 wherein said means comprise outwardly and inwardly adjustable members projecting from the head at different points along the working axis of the head.

6. In a honing or polishing tool, a rotatable head comprising separable clamping members, a leaf element clamped between the members and adapted to extend outwardly from the head and then in generally trailing relation to the clamped portion in respect to the direction of rotation of the head, clamping screws connecting the clamping members, and a flexible abrasive strip marginally clamped between said members, the margin so clamped being slotted inwardly from the edge of the flexible strip so that, without removing the screws, the strip can be mounted in clamping position with the screws extending through the strip.
